DESIGN FOR A COMBINED HEEL AND PLAT- FORM FOR A SHOE OR SIMILAR ARTICLE

Edwin J. Kapteyn, Los Angeles, Calif.

Application September 22, 1944, Serial No. 115,402

Term of patent 3½ years

(Cl. D7—5)

To all whom it may concern:

Be it known that I, Edwin J. Kapteyn, a citizen of the United States, residing at Los Angeles, in the county of Los Angeles and State of California, have invented a new, original, and ornamental Design for Combined Heel and Platform for a Shoe or Similar Article, of which the following is a specification, reference being had to the accompanying drawing, forming a part thereof.

Referring to the drawing:

Figure 1 is a perspective view of a combined heel and platform for a shoe or similar article, showing my new design.

Figure 2 is another perspective view taken from the other side.

Figure 3 is a view in side elevation.

Figure 4 is a top plan view.

Figure 5 is a transverse, vertical sectional view taken upon the line 5—5 of Figure 4 with the direction of view as indicated.

I claim:

The ornamental design for a combined heel and platform for a shoe or similar article, substantially as shown.

EDWIN J. KAPTEYN.
